WATCHCASE

David Megar, New York, and Maurice A. Popiel
and Jacob Schonholtz, Brooklyn, N. Y.

Application November 18, 1939, Serial No. 305,114

2 Claims. (Cl. 58—90)

This invention relates generally to watchcases, but more specifically to a watchcase construction having waterproof features.

The main object of the invention resides in the provision of a watchcase, the parts of which are easily assembled effecting water-tight joints between the assembled case and the movement, and between the movement, the winding stem, the pendant and crown respectively.

10 Another object of the invention is to produce a water-proof watch case which is simple, economical to manufacture, durable, water-proof and dust-proof, and which does not interfere with the efficiency of operation of the movement.

15 Another object of the invention resides in the provision of a watchcase which is made of a minimum number of parts, and wherein the bezel member is provided with a central opening, the edge of which is tapered to serve as a 20 water-proof valve seat for a non-breakable crystal; the said crystal being also provided with correspondingly tapered walls to sit in said valve seat in a water-tight and dust-proof manner without the utilization of packing between the 25 crystal and other members of the watchcase.

The watchcase of the present invention is characterized by features that render the connection between the crystal and the watchcase waterproof and dust-proof, that render the connection 30 between the crown, the winding stem and the watchcase water-proof and dust-proof, and that render the connection between the back and the watchcase water-proof and dust-proof.

These objects and other incidental ends and 35 advantages of the invention will hereinafter appear in the progress of the disclosure and as pointed out in the appended claims.

40 Accompanying this specification is a drawing showing a preferred form of the invention wherein corresponding reference characters designate corresponding parts throughout the several views and wherein:

45 Figure 1 is a plan view showing a watch incorporating a water-proof watchcase, said case being equipped with bracelet holding lugs.

Figure 2 is a transverse sectional view of Figure 1.

Figure 3 is an enlarged fragmentary and sectional view showing the upper portion of Figure 2.

50 Figure 4 is an enlarged and fragmentary view showing the water-proof and dust-proof connection between the bezel and the crystal of the watchcases as effectuated by the tightening of a central ring member.

55 In accordance with the invention and the

preferred form shown in the drawing, the watchcase comprises a central ring member 10 having a plurality of diametrically opposed openings 11, the outer surface of the cylindrical walls of said center member being externally threaded as indicated by numeral 12. Adapted to engage center 10 is a bezel 13 and a back 21. The bezel 13 is cylindrical in form, its upper portion being flared inwardly and terminating in a circular horizontal flange 14, the inner circular edge 15 of 10 said flange being tapered. An internal thread 16 on bezel 13 is adapted to engage thread 12 of center 10 while a lower reduced portion 15' on the inner surface of bezel 13 forms a housing 17 with center 10. An opening 13a in bezel 13 is 15 adapted to register with any one of the openings 11 of the center 10 whereby the winding stem 33 of movement 34 is permitted to penetrate center 10 and bezel 13 respectively as will hereinafter appear.

20 Bezel flange 14 is adapted to engage a non-breakable crystal 18, the latter having a downwardly and outwardly inclined wall 19 and a flange 20. As seen in Figure 4, inclined wall 19 sits against inclined edge 15 as a conical valve 25 on an inclined seat, while the upper surface of the flange 20 of crystal 18 abuts the lower surface of the bezel flange 14.

Center 10 as it is screwed into bezel 13 forces the end portion of crystal flange 20 into tight 30 engagement with the lower surface of bezel flange 14, thereby fixing crystal 18 at flange 20 and at wall 19 to the seat afforded by the undersurface of bezel flange 14 and by the inclined bezel edge 15 respectively. The inner portion of crystal 35 flange 20 adjacent the upper edge of center 10 is engaged by the edge portion of the top 34a of a watch movement 34 secured to and seated within a movement ring 31. The ring 37 at the lower edge is provided with a plurality of depending springable flanges 34b which are adapted to force the top 34a of movement 34 against the said inner portion of flange 20 when back 21 at an internally threaded wall 22 is screwed into place on center 10 as will hereinafter appear. 45 A dial 35 mounted on the top 34a of the movement 34 is preferably adapted to extend within the inner surfaces of inclined crystal wall 19.

Wall 22 of back 21 is adapted to penetrate 50 housing 17 containing a gasket 24 and engages 50 the lower threaded end of center 10. When back 21 is tightened onto center 10 against springable flanges 34b, the seating of crystal wall 19 and of crystal flange 20 in bezel edge 15 and bezel flange 14 respectively by center 10 is aided 55

by the engagement of the edge portion of top wall 34a with flange 20 to effectuate a water-proof and dust-proof joint. The connection, as has been above mentioned, between crystal wall 19 and 5 bezel edge 15 acts as a conical valve and seat by virtue of the inclination of the said members.

In providing a simply constructed and normally operated water-proof and dust-proof connection between the crown and the watchcase, 10 a pendant tube 25 at its inner end is attached to bezel 13 around opening 13a by a soldered joint or equivalent thus fixing tube 25 as an integral part of bezel 13. A gasket 26 is placed at the lower end of tube 25 and packing 28 is placed 15 thereabove, a gasket 27 being situated below the upper edge of tube 25 forming the top cover for the packing. Thereafter, the upper portion of tube 25 is turned inwardly over gasket 27 to form an enclosing flange 29 as best shown in Figure 3. 20 A cylindrical core 31 formed integrally with a crown 30 extends inwardly of the tube 25 penetrating gasket 27, packing 28, gasket 26 and opening 13a, the said core 31 being provided with an internal screw thread 32 to receive the externally threaded winding stem 33. However, before crown 30 is applied, the winding stem 33 is first forced into the movement 34 after the watchcase and movement have been assembled together except for the attachment of back 21 25 by passing stem 33 through the gaskets and packing of the pendant tube 25 and through the bezel opening 13a and aligned center piece opening 11. When this is done, the stem is fixed to the movement by means of a screw on the movement, the said screw not being shown in the drawing.

The reason for the provision of a plurality of openings 11 in center 10 is to insure registration of any one opening 11 with opening 13a 40 of bezel 13 after center 10 is tightened against bezel flange 20. Numeral 36 indicates bracelet holding lugs which are affixed in the usual fashion to bezel 13.

It is to be observed that crown 30 is used to 45 wind and to move the hands of the watch in the usual manner and at the same time is connected with the winding stem 33 in a water-proof and dust-proof manner. In disassembling the watchcase, back 21 is removed from center 50 10 and the winding stem disengaged from the movement by loosening the attachment screw. Thereafter, both the crown 30 and stem 33 are removed bodily from bezel 13, whereupon ring 37 secured to movement 34 is withdrawn from center 10. Thereafter, center 10 is unscrewed 55

from bezel 13 to permit the rearward withdrawal of crystal 18.

We wish it understood that the bezel 13 and crystal 18 of the above described water-proof and dust-proof watchcase may assume an external shape of any geometric form, and that minor changes and variations in the material, construction, integration, cooperation and shape of parts, may all be resorted to without departing from the spirit of the invention and without departing from the scope of the appended claims.

We claim:

1. A watchcase of water-proof and dust-proof construction comprising in combination movement holding means including threadedly engageable center and bezel members, a non-breakable crystal seated between the upper portions of the center and bezel members, a housing between the lower portions of the center 20 and bezel members, a gasket seated within said housing, a back threadedly engageable with the center within said housing and adapted when tightened to impinge against said gasket to form a water-tight and dust-tight joint between 25 the bezel, the center and the back and to wedge the crystal against the upper portion of the bezel to form a water-tight and dust-tight joint between the crystal and the bezel.

2. A watchcase of water-proof and dust-proof 30 construction comprising the combination of a center, a bezel adapted to threadedly engage said center, a housing between the lower end of said center and bezel, the bezel at the upper end having a flange terminating in an inclined 35 seat, a non-breakable crystal having an inclined wall to engage said seat and a flange to engage the bezel flange, the center being adapted to partly maintain the crystal flange against the bezel flange when screwed into said bezel and 40 to receive the watch movement and dial, the movement being adapted to engage the crystal flange adjacent the upper edge of the center, a gasket within said housing and a back threadedly engageable with the center and being adapted 45 when tightened to impinge against said gasket to form a water-tight and dust-tight joint between the bezel, the center and the back and to force the top of the movement against the crystal flange thereby forming a water-tight and dust- 50 tight joint between the crystal and the bezel.
